UNITED STATES PATENT OFFICE.

EDWARD ISAACSON, OF ST. CLOUD, MINNESOTA.

APPARATUS FOR OILING THE CYLINDERS AND PISTONS IN SURFACING MACHINES.

Application filed November 10, 1923. Serial No. 674,018.

To all whom it may concern:

Be it known that I, EDWARD ISAACSON, a citizen of the United States, residing at St. Cloud, in the county of Stearns and State of Minnesota, have invented certain new and useful Improvements in Apparatus for Oiling the Cylinders and Pistons in Surfacing Machines, of which the following is a specification.

10 This invention relates to apparatus for oiling the cylinder and piston in a surfacing machine and consists in the novel features and steps hereinafter described and claimed.

A surfacing machine is one used for raising and lowering large hammers at a rapid rate of speed and dropping them upon the surface of rock which it is desired to smooth. Such machines are used in granite and marble building and monument work for the 15 purpose of getting the stone in a presentable and marketable shape. The machine is run by compressed air which is forced into a cylinder and allowed to escape at short intervals. As the air enters the cylinder it 20 forces the piston which holds the hammer, in a downward direction. Considerable difficulty has been encountered in properly lubricating the cylinder and piston. Many machines have no oilers at all and others simply pour oil into a cylinder in large quantities which only lasts for a few minutes and disappears around the piston and escapes 25 through the exhaust.

With this object in view the invention 30 consists of a chamber adapted to retain the oil and which is fitted in the top of the cylinder. The chamber is provided at its top with an opening which is normally closed by a removable plug. A spider is 35 located interiorly of the chamber and a needle valve is screwed therein. A coil spring is interposed between the spider and the head of the needle valve and serves to hold the valve at an adjusted position. At 40 its lower end the chamber is provided with an oil outlet opening which is located opposite the pointed end of the needle valve. The air inlet and exhaust pipes communicate 45 with the chamber at points above the spider. A nipple is connected with the lower end of the chamber and is also connected with the cylinder of the surfacing machine hammer. A movable ball is retained in the nipple and 50 normally rests upon an inturned seat provided at the lower end thereof and closes the 55 passageway through the nipple. As the air

enters the cylinder the ball is lifted from its seat and the oil drops into the cylinder and is administered to the parts. When the air pressure is interrupted the ball falls to the 60 seat and the flow of oil is cut off.

In the accompanying drawings—

Figure 1 is a vertical sectional view of a machine hammer with the oiling chamber attached.

Figure 2 is an enlarged sectional view of the oil chamber detached.

Figure 3 is a transverse sectional view of the same.

Figure 4 is a plan view of the nipple.

The machine to which the oiling system is applied comprises a cylinder 1 which is mounted in a suitable frame 2. A piston 3 is slidably mounted in the cylinder in a usual manner. An air pipe 4 connects with the upper part of the cylinder and an exhaust pipe 5 also connects with the upper part of the cylinder in a usual manner.

A nipple 6 is screwed in the top of the cylinder and is provided at its lower end 80 with an inturned valve seat 7. A ball 8 is retained in the nipple and normally rests by gravity upon the seat 7. A cross bar 9 extends across the interior of the nipple at the upper portion thereof and serves to prevent the ball from passing out of the top of the nipple when the air pressure is on in the cylinder as will be hereinafter explained. A chamber or casing 10 is screwed upon the upper end of the nipple and is provided at 90 its lower end with a reduced outlet opening 11 which is centrally disposed with relation to the nipple. A spider 12 is disposed transversely across the intermediate portion of the chamber and carries at its center an internally threaded annulus 13. A needle valve or pin 14 is provided between its ends with an enlarged portion 15 which is screw threaded in the annulus 13. The needle valve 14 is provided at its upper end with a head 17 which in turn is provided with a screw driver groove 17. A coil spring 18 is interposed between the spider and the head 16 of the needle valve and serves to hold the needle valve at an adjusted position with 100 relation to the oil outlet opening 11 at the bottom of the chamber and after the valve has been set. The spring 18 is of general cone shape configuration in side elevation so that the coils thereof may nest within each other when the spring is compressed.

The chamber 10 is provided at its top with

an opening 20 which is normally closed by a detachable plug 21, there being a leather washer 22 interposed between the head of the plug and the top of the chamber, in a usual manner. The plug is provided with a transversely disposed opening 23 through which a nail or other object may be passed when it is desired to turn the plug.

The operation of the device is as follows. 10 The air under pressure enters the cylinder 1 through the pipe 4 and operates the piston 3 in the cylinder in a usual manner. At the same time the air pressure lifts the ball 8 from the seat 7 and the oil, which is contained in the chamber and nipple, passes around the ball 8 and drops into the cylinder and upon the piston and lubricates the parts. When the air pressure is interrupted the ball 8 falls by gravity to the seat 7 and 15 closes the passageway of the oil through the nipple and hence the passing of the oil from the chamber and nipple to the interior of the cylinder is automatically interrupted.

By removing the plug 22 from the chamber, 20 the end of a screw driver, not shown, may be inserted in the groove 17 of the

head 18 of the needle valve and the said valve may be adjusted so that its lower pointed end is disposed at a proper distance from the opening 11 and hence the quantity of the oil which flows from the chamber into the nipple may be regulated as required to effect the desired results in an economical manner. 20

Having described the invention what is claimed is— 35

An oiler comprising a substantially elliptical chamber provided at one end with a socket and at its opposite end with an opening, a plug closing said opening, a nipple screwed in the socket and having a seat and a cross bar spaced from the seat, a ball carried in the nipple between the seat and the cross bar, the end portion of the chamber having a needle valve seat which enters the socket, a spider located in the chamber, and a needle valve extending through and having a screw threaded engagement with the spider. 40

45 In testimony whereof I affix my signature.

EDWARD ISAACSON.
